Ruth C. Haskell,
Administratrix.
By W. C. Brewster,
Attorney.

UNITED STATES PATENT OFFICE.

RUTH C. HASKELL, OF PHILADELPHIA, PENNSYLVANIA, ADMINISTRATRIX OF CHARLES S. HASKELL, DECEASED.

KEY AND KEY-ACTION FOR ORGANS OR SIMILAR MUSICAL INSTRUMENTS.

No. 921,610.

Specification of Letters Patent.

Patented May 11, 1909.

Original application filed October 16, 1905, Serial No. 283,014. Divided and this application filed July 18, 1907.
Serial No. 384,486.

To all whom it may concern:

Be it known that CHARLES S. HASKELL, deceased, late a citizen of the United States, residing in the city and county of Philadelphia, State of Pennsylvania, did invent new and useful Improvements in Keys and Key-Actions for Organs and Similar Musical Instruments, of which the following is a specification.

10 This invention relates to improvements in keys for organs and similar musical instruments and certain devices associated with the said keys, and the principal object of the said invention is the provision of self-adjusting key mechanism for the key manual; that is to say, keys, the construction and arrangement of which render unnecessary the presence or use of special adjusting means, as, for instance, screws, by means of which 15 20 the contraction and the expansion of the various parts of the structure, including the supports for the keys, are compensated for.

Other objects of the invention will become apparent from the detailed description 25 thereof.

A convenient embodiment of the invention is shown in the accompanying drawing, but it is to be understood that changes in the details of construction may be made without departing from the scope of the invention.

The drawing shows a section of a portion of an organ one key being represented in side elevation and portions of a second key 35 in side elevation.

This application is a division of the co-pending application for patent numbered 860,745, and it is to be understood that the number and arrangement of keys may be the same as is illustrated and indicated in the 40 said patent, or the number and arrangement may be varied, if desired.

In the drawing, 1 designates a portion of a key box which is of usual or desired construction.

2 designates the organ keys, of which two only are shown. In order that the outer ends of the keys may be held normally in an upward position, as indicated in the drawing, there are provided springs 4, one of which is located under each key of the key manual and is connected to such key, and

the outer end of which is separated or bent away from the key and is in contact with a buffer or bar 5 which limits the downward movement of the outer end of the keys. It is to be understood that normally the said springs are under greater or less tension. The inner end of each key of the key manual extends inwardly to points underneath a wind box.

In the drawings but one wind box 10 is shown. Such additional keys and wind boxes as may be employed have the same construction and relative arrangement as is shown in the drawings. Valves 15 are located in the wind boxes, which valves are adapted to close ports 16 and to be opened by means of valve stems 17 connected thereto. The lower ends of said valve stems project through perforations 18 in line with the ports 16. The perforations 18 are slightly greater in diameter than the diameters of the valve stems so that annular spaces are formed around the valve stems for a purpose 75 to be hereinafter stated. The lower ends of the said valve stems are provided with valves 19 which are adapted to close the perforations 18 when the valve stems 17 are raised to open the valves 15. The valves 19 are held upon the valve stems by means of buttons 19^a on the lower ends of the said valve stems.

The lower ends of the valve stems 17 are respectively located short distances immediately above the inner ends of the respective keys. Each of the valves 15 is supported by a spring 20 and is normally pressed down upon the bottom of the wind box in which it is located, as clearly shown in the drawings. The upper ends of the valve stems pass through the springs 20 as indicated.

In order that the keys may be self-adjusting, that is, in order that the keys may move up and down through short distances, due to the expansion and contraction of the supports 21, which are usually preferably of wood, without rendering necessary a re-adjustment thereof, there are provided the inner ends of each of the keys with a spring 22, the extreme inner free end of the spring being located, as previously stated, a short distance underneath the lower ends of the valve stems 17; that is, underneath the buttons 19^a.

By reason of the fact that the inner ends of the springs 22 are located a short distance underneath the lower ends of the said valve stems, the said keys may assume slightly different positions relatively to the said valve stems, due to the expansion and contraction of various parts of the structure, without coming into contact with the said valve stems. Also there may be accidental slight depression of a key without opening its corresponding valve 15.

As already indicated, 5 designates a buffer underneath the outer ends of the keys to limit the movement of such outer ends. Upward movement of the keys is limited by a buffer stop 24. The distance between the outer end of a key and its buffer 5 is such that when it is depressed and the inner end of its spring reaches the limit of its movement, the outer end of such key continues to move down, in consequence of which said spring is slightly bent and placed under tension. In other words, there is a certain amount of lost motion due to the fact that the distance through which the inner end of a key is permitted to move is relatively less than the distance through which the outer end of such key is permitted to move when it is depressed. There is also lost motion due to the fact that the inner end of the key, that is, the inner end of the spring, is located a short distance below the lower end of its corresponding valve stem 17.

As the valves 15 are held in position upon the bottom of the wind box in which they may be located by the springs 20, it is evident that the said spring must be weaker than the springs 22 at the inner ends of the keys, so that the tension of the said springs may be overcome by the springs 22 in their upward movement so as to open the valves 15. It is to be noted here that the springs 20 serve both the purpose of holding said valves in position upon the bottom of the wind box to close the ports or openings 16 leading from the said wind box and the said springs act as guides to return the said valves into accurate position after they have been elevated from their respective seats.

25 designates passageways (only one of which is shown) located in what may be termed the bottom of the wind box, the said passageways being connected to supply tubes or channels 26.

55 It is desirable that after communication between a wind box and the supply tubes or channels connected therewith has been closed by the valves 15, the air within the said tubes or channels should return quickly to normal pressure; that is, the pressure of the outside atmosphere. It is to accomplish this result that the annular spaces around the valve stem 17 within the perforations 18 are provided. The quick return of the air within 60 the supply tubes or channels to normal air

pressure prevents the speaking of the organs after a key or any number of keys of the key manual has been released and permitted to return to normal elevated position.

Having thus described the invention, I claim:

1. In organ construction, in combination, an organ key having a spring extension upon its inner end, a wind box provided with a port or opening, a valve for closing the said opening, means interposed between the said valve and the inner end of the said spring whereby the said valve may be opened, the said means being separated a short distance from the said inner end of the spring when the latter is at rest.

2. In organ construction, the combination of an organ key having a spring extension upon its inner end, a wind box provided with a port or opening, a valve for closing the said opening, a supply tube or channel communicating with the said opening, a perforation through the bottom of the said wind box, a valve stem extending from the said valve through the said perforation, the diameter of the said valve stem being less than the diameter of the said perforation, a valve upon the said stem which is adapted to close and open the said perforation, the said last-mentioned valve being adapted to be closed by the action of the said spring extension thereon.

3. In organ construction, the combination of organ keys having spring extensions upon their inner ends, a wind box provided with ports or openings, perforations through the bottom of the said box in alignment respectively with the said ports or openings, valves for closing the respective ports or openings, the said valves being provided with valve stems which extend through the said perforations, the diameters of the said stems being less than the diameters of the said perforations, valves upon the lower ends of the said valve stems underneath the said perforations, the lower ends of the said valve stems being located normally a short distance from the inner ends of the spring extensions and adapted to be raised by the upward movement of the said extensions, whereby the said valves are adapted to open the said ports or openings and close the said perforations, and supply tubes or channels communicating respectively with the said ports or openings.

4. In organ construction, a wind box, a plurality of openings communicating with the said wind box, a plurality of supply tubes or channels extending into the bottom of the said wind box and communicating with the said openings, perforations in the bottom of the said box in alignment with the said openings, valve stems having valves upon the opposite end portions thereof, which are adapted to close the said openings and the said perforations, springs in the said

wind-box normally holding the said valves in position to close the said openings and to open the said perforations, the upper ends of the valve stems extending through the said 5 springs whereby the latter act as guides to hold the valves in proper position, and keys having spring extensions upon their inner ends which are separated normally from the lower ends of the said valve stems.

10 In testimony that I claim the foregoing as

the invention of CHARLES S. HASKELL, deceased, I hereunto sign my name this seventeenth day of July, 1907.

RUTH C. HASKELL,
*Administratrix of the estate of Charles S.
Haskell, deceased.*

In the presence of—

RUTH E. HASKELL,
JOSEPH L. FITZPATRICK.
